Fred C. Nakamura, Los Angeles, Calif.

Application September 4, 1956, Serial No. 42,834

Term of patent 7 years

(Cl. D83—1)

FIG 1

The characteristic features of my design for the neck and body massage block disclosed reside in pattern on the end portions as best shown in Figs. 3 and 4.

The bottom and rear portions of my neck and body massage block are substantially plain.

I claim:

The ornamental design for a neck and body massage block, as shown and described.
